SHOE LAST

George Clausing, Portsmouth, Ohio, assignor to
Vulcan Corporation, Portsmouth, Ohio

Application October 6, 1945, Serial No. 620,697

6 Claims. (Cl. 12—135)

1

This invention relates to improvements in shoe lasts and has for its principal object the provision of a means for precluding the formation of score marks or ridges on the insoles of shoes made upon a last having rectilinearly movable parts.

Another important object of this invention is to provide a two part last which has a novel expansive and contractive action for permitting ready insertion of said last into a shoe and also its removal therefrom.

A further objection of the invention is to provide in a two part last having a rectilinearly directed expansive and contractive action a means for preventing scoring and ridging of the insole of shoes made thereon.

A still further object of the invention is to provide a simplified and effective device for attaining the aforementioned advantageous objects.

Another object of the invention is to provide a novel means for preventing ridge formation on shoe insoles made upon a two part last, said means being adapted to cooperate with certain last parts and their functions to secure positive action and improved, reenforced last parts.

Other objects of my invention will be apparent from the following description and drawings which illustrate a preferred embodiment of my invention, it being understood that the foregoing statement of the objects of my invention is intended generally to explain the same without limiting it in any manner.

In the drawings:

Fig. 1 is a side, elevational view of my shoe last in last expanded position, parts being broken away to clearly show the relation of parts.

Fig. 2 is a side elevational view of the shoe last illustrated in Fig. 1 in contracted condition, parts being broken away to disclose other parts in central, longitudinal cross-section.

Fig. 3 is a fragmental plan view of my last bottom.

Fig. 4 is a cross-sectional view taken on line 4—4 of Fig. 1.

My shoe last comprises a fore part 5 and a back part 6 which are arranged for relative movement into expanded or contracted position by means of a pair of parallel guide rods 7 and 8. As clearly indicated in Figs. 1 and 2 the guide rods extend longitudinally of the last and have their respective axes disposed in a plane inclined to the longitudinal axis of the last, said longitudinal axis being parallel to the mean bottom surface 9 of the last back part, which as illus-

2

trated in Fig. 2, is in a substantially horizontal plane for the particular last illustrated.

The guide rods 7 and 8 are slidably received in inclined bores 10 and 11 respectively formed in the fore part 5, whilst the rear portions of said rods are held in bores 12 and 13 respectively formed in the back part 6. Wood plugs 14 maintain the guide rods in operative position within their respective bores. Each of the parts may be provided with the usual thimbles or bushings 15 for mounting the last on a suitable jack (not shown). It will therefore be noted that when the last parts are moved from last expanded position, illustrated in Fig. 1, to last contracted position as shown in Fig. 2, or vice versa, the inclined guide means imparts a relative movement to said last parts which is directed along a rectilinear path inclined at an acute angle with respect to the longitudinal axis of the last. The acute angle has legs formed by the longitudinal axis of the last and the extension of the rectilinear path of the guided heel part. These legs diverge from the apex in a direction rearwardly of the last. For example, when the last moves from expanded to contracted positions the back part 6 moves downwardly on the guide rods toward the forepart 5, the mean bottom surface 9 of the back part retaining a horizontal position throughout said relative movement. This action facilitates the insertion of my last into a shoe for upon locating the fore part 5 in the position it normally occupies within the toe portion of said shoe it is only necessary to move the back part toward its operative expanded position, said movement permitting the bottom 9 of the back part to gradually approach the heel insole of the shoe and to firmly contact said insole in said last expanded position. In removing the last from the shoe a reverse action occurs, said back part bottom 9 gradually moving away from the heel insole as the back part is moved to its contracted position whereupon the last may be readily removed from said shoe.

The means for preventing the formation of ridges or score marks on the insoles of shoes made upon my two part last comprises a heel plate 16 fastened to the bottom surface of the back part 6 by a plurality of nails 17. The heel plate has a forwardly extending portion 18 which terminates in a tapered, transverse end 19. As clearly indicated in Fig. 1 the tapered end 19 of this extension engages the lower rear edge 20 of the fore part 5 when the last parts are in expanded position, said lower edge 20 having a complementary taper to receive the tapered end 19 on the heel plate extension. The novel relative movement

between the last parts and the tapered engaging surface of the fore part 5 and the heel plate extension 18 permit the extension to snugly engage the fore part to create a rigid last construction which is placed under tension by the engagement of the extension with the fore part. The plate also acts as a means, with the two guide rods, for preventing undue twist between the back part and the fore part of the last during the sole laying and leveling operations. It will therefore be understood that said extension 18 bridges the gap between the insole engaging surfaces of a two-part last having rectilinearly directed expanding and contracting action. When the last is in its normal expanded position said extension offers a rigid means which is flush with the last under surface, for contacting the shoe insole to prevent the formation of transverse ridges or score marks on the insole when operative pressure is applied on said shoe during the manufacturing process.

A means for locking the last parts in expanded position is a device which is set forth in Patent No. 2,419,944 granted on May 6, 1947, and which may comprise a flat link 21 pivotally mounted on a transverse pin 22 carried by the back part. The free end of the link is provided with a notch 23 which cooperates with a transverse pin 24 carried by the fore part to hold the parts in expanded position. The link is urged against the pin 24 by a compression spring 25 seated in a depression formed in the back part 6 and bearing at its upper end against the bottom of said link. The lock may be tripped by a suitable bumper tool which bears downwardly on the central portion of the link against the action of the spring 25 and moves the notch 23 out of engagement with the transverse pin 24. The last parts may then be manually moved together to the contracted position indicated in Fig. 2.

What is claimed is:

1. A shoe last comprising a fore part, a back part, and longitudinally extending inclined guide means for imparting rectilinear movement to said last parts along a path inclined at an acute angle relative to the longitudinal axis of said last upon extension, and contraction of the parts thereof, said acute angle having legs formed by the intersection of the rectilinear path and the longitudinal axis of the last which diverge in a direction rearwardly of the last.

2. A shoe last consisting of a fore part, a back part, and a pair of longitudinally extending guide rods having their axes disposed in a plane inclined with respect to the longitudinal axis of the last, said guide rods imparting rectilinear movement to said last parts along a line inclined relative to the longitudinal axis of the last.

3. A shoe last consisting of a fore part, a back part, and a pair of longitudinally extending guide rods having their axes disposed in a plane inclined with respect to the longitudinal axis of the last, said guide rods imparting rectilinear

movement to said last parts along a path lying in the vertical plane of the longitudinal axis of the last.

4. A shoe last comprising a fore part, a back part, a pair of longitudinally extending inclined guide rods for imparting rectilinear movement to said last parts along a path inclined at an acute angle relative to the longitudinal axis of said last upon extension or contraction of the last parts, the legs of said acute angle being formed by the intersection of said rectilinear path and the longitudinal axis of the last and which diverge in a direction rearwardly of the last.

5. A shoe last comprising a fore part having a tapered portion along its lower rear edge, a back part normally spaced from the fore part and having a mean bottom surface parallel to the longitudinal axis of the last, parallel guide rods for the last parts having their axes disposed in a plane inclined relative to the mean bottom surface of the back part, said guide rods being adapted to provide relative movement for each last part along a line inclined with respect to the longitudinal axis of said last, a heel plate fixed to the bottom of the back part and having a forwardly extending portion, a tapered transverse edge on the extending portion for normally engaging the tapered edge of the fore part, and means for locking the parts in normal expanded position.

6. A shoe last comprising a fore part having a tapered portion along its lower rear edge, a back part normally spaced from the fore part and having a mean bottom surface parallel to the longitudinal axis of the last, parallel guide rods for the last parts having their axes inclined relative to the mean bottom surface of the back part, said guide rods being adapted to provide relative movement for each last part along a line inclined with respect to the longitudinal axis of said last, a heel plate fixed to the bottom of the back part and having a forwardly extending portion, a tapered transverse edge on the extending portion for normally engaging the tapered edge of the fore part, and means for locking the parts in normal expanded position.
